(No Model.)

O. COLBORNE.
VERTICAL ANTI-FRICTION ENGINE.

No. 423,515.

Patented Mar. 18, 1890.

UNITED STATES PATENT OFFICE.

OLIVER COBORNE, OF CHICAGO, ILLINOIS.

VERTICAL ANTI-FRICTION ENGINE.

SPECIFICATION forming part of Letters Patent No. 423,515, dated March 18, 1890.

Application filed November 5, 1888. Renewed February 17, 1890. Serial No. 340,962. (No model.)

To all whom it may concern:

Be it known that I, OLIVER COBORNE, a citizen of the United States, residing at Chicago, in the county of Cook and State of Illinois, have invented certain new and useful Improvements in Vertical Anti-Friction Engines; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 In the drawings, Figure 1 is a vertical sectional elevation of my improved engine through the center of the cylinders. Fig. 2 is an enlarged section of one of the anti-friction rollers. Fig. 3 is the eccentric with one 20 guide band or ring left off to show the position of the anti-friction rollers. Fig. 4 is a sectional elevation of the valve through the dotted line in Fig. 1. Fig. 5 is a cross-section of the valve through the dotted line in 25 Fig. 4.

Like letters indicate like parts in the several views.

My improved engine consists of a single casting forming the base and united to the 30 flanges B of the cylinders C C'. The cylinders being cast in a single piece can be lifted off, allowing easy access to the shaft and eccentrics. The cylinders C C' are provided with long pistons D D', which are held firmly 35 down on the loose ring c of the eccentric E by the steam, which is admitted only to their top sides or heads, as shown in the drawings, thus: The piston D' of the cylinder C' having completed its stroke, the valve F will 40 have been lifted by the eccentric H until the port e has been uncovered, admitting steam to the top of the piston D of the cylinder C, while, the port f of the cylinder C' having been uncovered, the steam which has done 45 its work will be exhausted into the annular space around the valve and out through the opening in the back side of the valve-casing. (Shown by the dotted-line circle marked g.) When the piston D has completed its stroke, 50 the valve F will have been pushed down by the steam following the eccentric H until the

valve has dropped below the port f. Steam coming in at the steam-pipe (shown by the dotted circle h) will enter the valve at i i, passing up through and over the top of the 55 valve, and entering the steam-port f. The preponderance of pressure being always on the top end of the valve keeps it in close contact with the eccentric H, which actuates it. In case of its use for large engines, where the 60 friction would be considerable, this eccentric may be fitted with anti-friction rollers, the same as the large eccentrics E. The pistons D and D' are by the steam held firmly in contact with the eccentrics, so that no lost 65 motion on account of wear can affect them.

I am aware that eccentrics in place of cranks have been used on the shafts of steam-engines as a means of converting the reciprocating movements of the piston into a rotary movement of the shaft, and that disks 70 rotating upon the rod connecting the pistons of two cylinders and inclosing an eccentric upon the engine-shaft between them have been used. I do not therefore claim such an 75 arrangement of parts, but limit my claim to the specific construction and arrangement of parts shown and described, in which the pistons of the different cylinders are not positively connected with each other or with the 80 eccentric, but are free to move independently of the eccentrics and of each other, as described.

Having thus described my improved engine, what I claim as new, and desire to secure by Letters Patent, is—

In a double vertical engine, the combination of the cylinders, the pistons resting directly upon but not connected to the anti-friction rings encircling the eccentrics E, the 90 eccentric H, and the valve F, its lower end retained in contact with the periphery of the eccentric by the pressure of steam upon its upper end, all arranged for joint operation substantially as shown and described. 95

In testimony whereof I affix my signature in presence of two witnesses

OLIVER COBORNE.
